ELECTRON TUBE BASE

Bruce A. Coffin, Peabody, Mass.

Application August 2, 1940, Serial No. 349,759

4 Claims. (Cl. 250—27.5)

This invention relates to an electrical connector, and specifically to a tube base for an electronic tube or similar device.

The invention has for an object to provide a novel and improved tube of the type provided with a metallic shell forming a part of the base and in which provision is made for electrically and mechanically connecting the metallic shell to a ground connection terminal in a simple and efficient manner, and whose construction is such as to minimize the number of assembly operations whereby the tube may be more economically produced.

Another object of the invention is to provide a novel and improved base for a tube in which the metallic shell portion of the base is provided with an integral ground connection strap and whose construction is such as to facilitate the assembly of the various parts of the tube whereby to effect a substantial economy in the cost of production.

A further object of the invention is to provide a novel and improved tube of the character described embodying a central metallic shield member, and in which provision is made for connecting the shield member together with the metallic shell to a ground connection terminal in a simple, economic and efficient manner.

In its broader aspects, the invention contemplates a novel electrical connecting unit embodying a metallic shell in which provision is made for grounding in a novel and improved manner.

With these general objects in view and such others as may hereinafter appear, the invention consists in the electrical connector, in the electronic tube and in the various structures, arrangements and combinations of parts hereinabove described and particularly defined in the claims at the end of this specification.

In the drawing illustrating the preferred embodiments of the invention, Fig. 1 is a cross-sectional view of an electronic tube embodying the present invention, the section being taken on the line 1—1 of Fig. 2; Fig. 2 is a plan view in cross-section of the base portion of the tube shown in Fig. 1; Fig. 3 is a view similar to Fig. 2 showing a modified form of the invention; Fig. 4 is a side elevation detail of the insulating portion of the base to be referred to; and Fig. 5 is a cross-sectional view, similar to Fig. 1, showing a different embodiment of the invention.

In general, the preferred and illustrated embodiment of the present invention contemplates a novel and improved construction of electronic tube adapted to facilitate assembly of the various parts of the tube and to enable the same to be

more economically produced. The base portion of the tube preferably includes an insulating disk provided with the usual connection pins including a grounding terminal. The insulating disk is adapted to receive a metallic shell in assembled relation therewith, and in the fabrication of the tube, it is necessary to connect the metallic shell to the ground connection terminal for the purpose of grounding the shell.

In accordance with the present invention, a grounding lug or strap is formed integrally with the metallic shell and is designed so that when assembled with the insulated disk, the strap will extend to the grounding terminal. The strap may then be secured to the top of the grounding terminal or connection pin in any suitable or convenient manner such as by clamping the lug under the head of the terminal pin or by soldering or welding the parts together. This results in the elimination of one of the wires formerly required to be inserted into the hole in the terminal and greatly facilitates the assembly operation.

When the tube is of the type requiring a central shielding member, in the form of a metal cylindrical member, this shield must also be electrically connected to the grounding terminal. Prior to the present invention, this connection was made by soldering or otherwise suitably securing a wire, one end to the shield and the other end to the grounding terminal. In accordance with the present invention, provision is made for extending the integral grounding lug into contact with the central tubular shield to be soldered or otherwise secured thereto, thus eliminating a second wire which formerly was necessary to be extended into the ground connection pin.

In practice, a preferred form of the invention may comprise a metallic shell stamped out of one sheet of metal to provide an annular portion having a strap connection horizontally extended from the lower edge of the annular portion to a ground connection, and a central portion integral with said strap having an opening therein adapted to receive the central shielding member in press fit or drive fit engagement. Additional strap extensions leading from the lower edge of the annular portion to the central portion serve as supporting members whereby to form an integral unit electrically connecting the shell and the central shielding member to a common grounding terminal.

Referring now to the drawing, Fig. 1 represents a tube which may comprise a bulb 10 containing the several elements of a thermionic valve, not shown, and a base portion or insu-

lating disk 12 composed of dielectric material. The insulating disk 12 is provided with the usual contact terminals or pins 14 spaced about a central locating plug or key 16. The base also includes a cylindrical shell portion 18 composed of metal which fits over a ridge portion 20 and on top of a shoulder 22 provided on the disk. The shell 18 is preferably secured to the disk 12 by bending the lower edge of the shell inwardly at selected points 24 into grooved portions 26 provided therefor. The base thus formed provides a cup-shaped receptacle in which the bulb 10 is secured.

As illustrated in Figs. 1 and 2, a preferred form of the electrical connecting unit contemplates a unitary grounding connection between the cylindrical shell 18 and the selected contact terminal or pin 14 and between a central shielding member 38 and the selected contact terminal. As herein shown, the cylindrical shell is provided with a strap member 28 extending inwardly from and integral with the lower edge of the cylindrical shell 18. The strap member is provided with an enlarged portion 30 having a hole 32 therein which coincides with the center of one of the terminal pins 14 when assembled with the disk. The strap 28 is extended beyond the terminal and is provided with a second enlarged portion 31 centrally disposed with relation to the shell 18 and having an opening 33 therein adapted to receive the central shielding member 38 in press fit or drive fit engagement therewith. As shown in Fig. 2, additional strap connections 35, 37 are extended from the lower edge of the cylinder to the centrally disposed enlarged portion 31 which serve as supporting members, the provision of which also serves to facilitate the fabrication of the unit in the stamping out process.

As shown in Fig. 1, the metal cylindrical shield member 38 is inserted into and extends above the hollow portion within the locator plug 16 for the purpose of providing an electrostatic and electromagnetic shield between the individual stem connection leads and between the individual terminal pins 14 of the tube. In the preferred embodiment of the invention, the central shielding member 38 is provided with a beaded or shouldered portion 39 which is arranged to seat against the enlarged portion 31 of the shell connection when assembled therewith. The lower portion of the shield 38 is preferably tapered slightly, as illustrated.

As shown in Figs. 1 and 2, the metal connection pins 14 are secured to the insulating disk 12 by inserting them through the holes provided therefor and then swaging or bending over the extended portions to fix them in place. An enlarged portion 34 of the pins serves as a shoulder to engage the underside of the disk. In order to secure the grounding lug 28 to one of the terminal pins 14, the end of the terminal pin selected is extended through a hole in the insulating disk and through the hole 32 in the lug and the extended end is likewise swaged or bent over the top of the enlarged portion 30, as illustrated. Although the preferred method of connecting the strap 28 and the selected terminal 14 is as above described, it will be understood that such connection may be made in various ways including welding, soldering or crimping one to the other.

In practice, a predetermined terminal pin is selected to serve as the ground connection, and as herein shown, in order to assure proper regis-

tration of the strap 28 with the pre-selected pin 14 when assembling, a plurality of grooves or clearance channels 36 are provided in the disk 12 which extend through the ridge portion 20 and into which the strap connections 28, 35, 37 are arranged to fit. Such grooved portions in addition to aligning the grounding lug with the proper terminal also serve to lock the cylindrical shell 18 to the insulating disk to prevent relative rotary movement between the parts. The grooved portions may be extended slightly below the shouldered or flanged portion 22, as indicated at 37 in Fig. 4, to present the top of the strap 28 flush with the top of the shouldered portion 22 of the disk so that, when assembling, a standard length of pin 14 may be used.

Referring now to Fig. 3, where the tube is of the type not provided with a central shielding member, the strap 28 may extend only to the terminal 14 as illustrated. The strap may be provided with an enlarged portion 30 having a hole 32 through which the pin 14 is extended and fixed in a manner similar to that as described in connection with Fig. 2.

A modified form of the electrical connecting unit including a central shielding member 38 is illustrated in Fig. 5. As therein shown, the connection to the shield 38 is preferably made by extending the grounding strap 28 beyond the terminal point a sufficient distance to contact the member 38. In its preferred form, the extended strap is bent upwardly as indicated at 40 and the upright portion is soldered, welded or otherwise secured to the shielding member as by being formed integrally therewith to form a support for the latter and to provide an efficient grounding connection.

From the above description, it will be observed that the novel construction of the tube base of the present invention provides a simple and efficient grounding connection from the metallic portion of the base to the grounding terminal and from the inner shielding member to the same terminal and that, as a result of such construction, the assembling of the base is facilitated and the number of assembly operations is substantially reduced to a minimum.

For some purposes the metallic shell 18 may have fitted in telescoping relation thereon or thereover, an outer metallic shield member indicated in dotted lines in Fig. 1 as 19. As also shown in Fig. 1, the disk 12 is preferably of a diameter so as to present the periphery thereof flush with the outside diameter of the outer metallic shield member 19.

The present tube base is particularly useful in the manufacture of electron discharge tubes, vacuum tubes, gaseous discharge tubes, thermionic valves, cathode ray tubes, and any other electronic tubes or devices, and in its broader aspects, the invention finds utility as a novel and highly useful electrical connector.

While the preferred embodiment of the invention has been herein illustrated and described, it will be understood that the invention may be embodied in other forms within the scope of the following claims.

Having thus described the invention, what is claimed is:

1. A tube base comprising a disc of insulating material having a plurality of connection pins extending from one face of said disc and spaced from the center of said disc, a cylindrical metal shell secured to said disc and extending from the other face of said disc adjacent the periphery

thereof, said shell having a plurality of circumferentially spaced metallic straps connected thereto and extending inwardly along said other face of said disc and being joined together adjacent the center of said disc, one of said straps having a portion provided with an aperture spaced from the center of said disc, one of said pins extending through said aperture and making electrical contact with said last mentioned strap.

2. A tube base comprising a disc of insulating material having a plurality of connection pins extending from one face of said disc and spaced from the center of said disc, a cylindrical metal shell secured to said disc and extending from the other face of said disc adjacent the periphery thereof, said shell having a plurality of circumferentially spaced metallic straps connected thereto and extending inwardly along said other face of said disc and terminating in a central portion common to said straps, said central portion being provided with an aperture, a shield member positioned within said aperture and electrically connected to said shell by said straps, said shield member extending axially from said one face of said disc between said pins for substantially their entire length and from said other face of said disc for a substantial distance within said shell, one of said straps having a portion provided with an aperture spaced from the center of one of said disc, said pins extending through said aperture and making electrical contact with said last mentioned strap.

3. A tube base comprising a disc of insulating material provided with a hollow centrally disposed guide member of insulating material extending axially from one face thereof, a plurality of connecting pins secured in said disc and extending from said one face of said disc said pins

surrounding said guide member, said disc being provided with a plurality of inwardly extending grooves in its other face, a cylindrical metal shell secured to said disc and extending from 5 said other face of said disc adjacent the periphery thereof, said shell having a plurality of integral metal straps extending inwardly and positioned in said grooves, said straps terminating in an integral central portion common to said 10 straps and provided with an aperture, a shield member positioned within said aperture and being electrically connected to said central portion, said shield member extending within said hollow guide member between oppositely disposed connection pins for substantially their entire length and extending axially from said other face of 15 said disc for a substantial distance within said shell, one of said straps being provided with a portion having an aperture spaced from the center of said disc, one of said pins extending through said aperture and being electrically connected to said last mentioned strap.

4. A tube base comprising a disc of insulating material having a plurality of connecting pins extending from one face of the disc, a cylindrical metal shell secured to said disc and extending from the other face of said disc adjacent the periphery thereof, a metallic strap connected to said shell 20 and extending along said other face of said disc, said strap having an aperture spaced from the center of said disc, one of said pins extending through said aperture and having a head adjacent said other face of said disc making electrical contact with said strap, the portion of said strap surrounding said aperture being positioned between said other face of said disc and the head 25 of said one pin.
